UNITED STATES PATENT OFFICE.

FREDERICK R. PARKER, OF CHICAGO, ILLINOIS.

ELECTROMAGNET.

1,226,617.

Specification of Letters Patent. Patented May 15, 1917.

Application filed February 19, 1904, Serial No. 194,392. Renewed September 23, 1916. Serial No. 121,905.

To all whom it may concern:

Be it known that I, FREDERICK R. PARKER, a citizen of the United States of America, residing at Chicago, in the county of Cook and State of Illinois, have invented a new and useful Improvement in Electromagnets, of which the following is a specification, reference being had to the accompanying drawings, illustrating same.

- 10 My invention relates in general to electrically-operable devices and more in particular to electromagnets, the devices herein particularly described being what are termed relays.
- 15 The principal objects of my invention are, to provide an improved device of the character above mentioned; to provide such a device in which the armatures or primary operating members are operated, or controlled, 20 by different energizations of, or different degrees of energy in, the device; to provide an improved arrangement of the armatures or primary operating members in such a device; to provide in a magnetically-operable 25 device of this character an improved arrangement of parts providing an open magnetic structure and a plurality of armatures or primary operating members adapted to substantially close the magnetic circuit of 30 the magnetic structure when attracted; and to provide a compact and efficient construction in such a device. Other objects will be apparent from the following specification.
- In the preferred form of my invention, I 35 provide an open magnetic structure, and an armature adapted to be actuated by a small amount of magnetism in the said structure to substantially close the magnetic circuit thereof. I also provide another armature 40 adapted to be attracted only upon a larger amount of magnetism in the magnetic structure, this latter armature also preferably helping to close the magnetic circuit of the device to a greater extent. Thus it will be 45 seen that the two armatures of the device may be actuated separately upon different energizations, or different degrees of energization, thereof. Thus, starting with the magnetism at zero and gradually increasing 50 it, one armature only will first be attracted, and as the magnetism is increased still further, the other armature will finally be attracted. When the magnetism is gradually 55 reduced, the last-mentioned armature only will first be released, and finally, with a

further reduction of the magnetism, the other armature will be released.

I preferably mount the armatures one over the other, so that they both tend to close the magnetic circuit at the same place, when attracted.

The magnetism for actuating the armatures may be produced or varied in any suitable manner. I preferably employ a winding on the magnetic structure for producing 65 the magnetism, and use any suitable means for varying the magnetizing power of the winding. It is not essential that this winding be a single-wound coil.

I also provide suitable switches, circuit 70 controlling means or operable portions to be operated by the armatures, and arrange them in suitable combinations as will be hereinafter shown.

I may also employ a casing for inclosing 75 the relay, to protect same from dust or injury to its parts.

I will now more particularly describe the preferred forms of my invention by reference to the accompanying drawings, in 80 which—

Figure 1 is a side elevation of one form of the device of the invention, showing the inclosing casing in cross-section; Fig. 2 is a 85 left end view of Fig. 1, also showing the casing in cross-section; Fig. 3 is a right end view of Fig. 1, without the casing and mounting strip; Fig. 4 is a top view of the relay shown in Fig. 1; Fig. 5 is a cross-sectional view of the relay of Fig. 1, taken on 90 line A—B of Fig. 4, with portions shown in elevation; Fig. 6 is a cross-sectional view of a portion of a modified form of the invention, taken the same as Fig. 5, with portions shown in elevation; Fig. 7 is a cross-sectional 95 view of another modified form of the invention, taken the same as Fig. 5, with portions shown in elevation; Fig. 8 is a cross-sectional view of a portion of still another modified form of the invention, taken 100 the same as Fig. 5, with portions shown in elevation; Fig. 9 shows the structure for supporting one armature; and Fig. 10 is a detail of a portion of the other armature and the roller bearing attached thereto.

Like characters refer to like parts in the several figures.

The winding *a* is placed upon the magnetic core *b* and is adapted to magnetize *b* when carrying a current of electricity. The 110

magnetic portion *i* is secured to one end of *b* by a bolt *r* provided with a nut or collar *r*₂, the bolt *r* also being adapted to hold the relay to a mounting strip *q* as shown. *r*₂ is 5 preferably a part of *r*. Insulating portions *d* and *c* are placed upon the respective ends of *b*, the ends of *b* being flattened or cut away as at *b*₃ to prevent the portions *d* and *c* from turning on *b* and also to form shoulders against which *d* and *c* rest when placed 10 upon the core *b*. The winding *a* is placed between the portions *d* and *c*. The strip *i* is secured to *d* and *c* by screws *x* and *s*, respectively, the spring members *m*, *n* and *o* being also mounted on screw *s* and insulated 15 from each other by insulating washers *t*. Screw *s* is also insulated from *m*, *n* and *o*. Thus it will be seen that the core *b*, strip *i* and insulating portions *d* and *c* are held 20 rigidly together by screws *x* and *s* and bolt *r*. Terminal posts *p*, *p* are secured to *c*, extending through same, and are used as terminal posts for the winding *a*. Springs *m*, *n* and *o*, and posts *p*, *p*, are adapted to receive circuit 25 conductors. Armature *f* is loosely pivoted to *i* by a screw *u* which passes through *f* and into *i*. A bushing *u*₂ is placed upon *u*, Fig. 9, the length of *u*₂ being greater than the thickness of *f* so that the armature *f* is free 30 to actuate when *u* is screwed up tightly. Armature *f* fits loosely upon *u*₂, the head of the screw *u* serving to hold *f* on *u*₂. *f* is provided with an insulating pin *l* which engages spring *n* and causes same to operate 35 when *f* is actuated. One end of core *b* is preferably cut away as at *z* to accommodate armature *f* when same is attracted. *f* is preferably provided with a non-magnetic covering at *v* which prevents *f* and *b* from 40 coming into actual contact with each other and sticking. Screw *k* extends through *i* and is an adjustment screw to limit the backward movement of armature *f*. *f* is preferably made of thin magnetic material. Armature *e* is also made of magnetic material 45 and is preferably thicker than *f*, it being loosely pivoted upon bolt *u* which is secured to a yoke *y*, the latter being secured to *d* by screws *y*₂. Screw *h* extends through armatures *e* and *f*, without interfering with their movement, and into *d*. *h* is an adjustment screw for armature *e*, limiting its backward movement. When *e* is attracted it rests 50 against *u* which serves as a stop for *e*. The same is true of *e*₂ and *u*, Fig. 6. Core *b* being cut away at *z* as shown, provides a portion of *b* close to *e*, which greatly increases the attraction of *b* on *e*. Armature *e* is preferably provided with an insulating roller *g* 55 loosely held upon bolt *g*₂ so as to provide a roller bearing adapted to engage spring *n* and operate same when *e* is actuated. *d*₂ is a casing adapted to fit over *d* and *c* and thus inclose the relay.

60 When the core *b* is slightly magnetized, by

a small current flowing in winding *a*, the armature *f* will be attracted to core *b*, as it is adjusted close to *b* and consequently may be very sensitive, but armature *e* will not be attracted, as it is farther away from core *b* and is not as sensitive as armature *f*. When armature *f* is attracted, it practically closes the magnetic circuit through itself, core *b* and strip *i*, and consequently armature *e* will not carry much of the magnetism until armature *f* is substantially saturated 70 and some of the magnetism is forced to take the path through armature *e*. When the current in coil *a* is increased, the magnetism in *b* increases, and when the magnetism increases sufficiently, armature *e* will become magnetized and be attracted. When the magnetism in *b* is gradually decreased, armature *e* is released before armature *f* is released. When the magnetism in core *b* is 75 changed abruptly from zero to a maximum, or vice versa, both armatures actuate approximately at the same time. When the armatures are attracted, they both help to complete the magnetic circuit.

In Fig. 5, both armatures operate the same spring *n*. Armature *f* breaks the contact between the springs *n* and *o* when attracted, but does not make contact between springs *n* and *m*. Armature *e* makes contact between springs *n* and *m* when attracted, continuing the movement of spring *n* from where armature *f* left off. When armature *e* is released it opens the contact between springs *n* and *m*, but does not close the contact between springs *n* and *o*. When armature *f* is released it closes the contact between springs *n* and *o*, continuing the movement of spring *n* from where armature *e* left off.

Each armature may, however, control independent contact members or switch members, as in Fig. 6, or both armatures may control the same contact, as in Fig. 8. In Fig. 6, armature *f* controls the contacts of spring *n*₃ with springs *m*₃ and *o*₃, and armature *e*₂ controls the contacts of spring *n*₂ with springs *m*₂ and *o*₂. In this figure I have shown armature *e*₂ without the roller *g* at its free end. In Fig. 8, armature *f* 105 moves spring *n*₆ into contact with spring *m*₆ when attracted, and then armature *e* moves spring *m*₆ out of contact with spring *n*₆ when attracted. When armature *e* of Fig. 8 is released it moves spring *m*₆ into 110 contact with spring *n*₆, and then when armature *f* is released it moves spring *n*₆ out of contact with spring *m*₆.

In Fig. 7 I have placed the armatures *f*₂ and *e* at respective ends of core *b*₂, the whole being mounted upon a suitable base *d*₄ by screws *s*₃, *s*₃. The terminals of winding *a* are connected to binding posts *s*₄. Screw *u*₃ forms a stop for armature *e*. The magnetic strip *i*₂ is secured to the insulating 120

members d_3 and c_3 by screws x , and is arranged so that the armatures f_2 and e form a closed magnetic circuit, through themselves, the strip i_2 and the core b^2 , when attracted. Springs m_4 , n_4 , o_4 , m_5 , n_5 and o_5 are mounted on bolt s_2 and are insulated from each other and from s_2 by insulating washers t_2 . Armature f_2 controls the contacts of spring n_5 with springs m_5 and o_5 , and armature e controls the contacts of spring n_4 with springs m_4 and o_4 .

The relay device shown in Figs. 1, 2, 3, 4 and 5 of the drawings forms the subject matter of my co-pending application Serial No. 160,599, on relay, which was filed on April 9, 1917. The electromagnetic device shown in Fig. 7 of the drawings forms the subject matter of my co-pending application Serial No. 841,730, on electromagnet, which was filed on May 29, 1914. The relay device shown in Fig. 8 of the drawings forms the subject matter of my co-pending application Serial No. 841,729, on relay, which was filed on May 29, 1914. All of these co-pending applications are divisions of this present application.

The relay of Figs. 1, 2, 3, 4 and 5, is utilized in, and claimed in connection with, the telephone system of my United States Letters Patent No. 767,953. The relay of Fig. 8 is utilized in, and claimed in connection with, the telephone system of my United States Letters Patent No. 1,103,909.

While I have shown and described particular details of construction in the various forms of this invention, I do not wish to limit the same to such exact details, as many modifications may be made in the devices shown without departing from the scope of the appended claims. Many different combinations of springs may be arranged to be operated by the armatures, to meet various requirements, and I wish it to be understood that such arrangements are contemplated in this invention.

Having thus described my invention, what I claim is:

1. In an electromagnet, the combination of an open magnetic structure comprising a core and another magnetic member secured to one end of the core, a magnetizing coil wound upon the said core, and two superposed armatures mounted so as to be actuated by the said structure, one armature being mounted loosely upon a collar carried by the said magnetic member and the other armature being pivoted upon the other side of the core from the said collar, both said armatures being arranged to complete the magnetic circuit when attracted, one of the said armatures requiring a stronger magnetizing force to attract it than that required to attract the other armature.
2. In an electromagnet, the combination of a magnetic core, an insulating head for
- each end of the core and placed thereon, each end of the core being flattened at one side to prevent the said heads from turning, a winding placed upon the core between the said heads and adapted to magnetize the said core, a second magnetic member secured to one end of the core by a bolt which is also adapted for mounting the electromagnet, the said second magnetic member being bent so as to extend parallel with the said core and being secured to the said heads, an armature of thin magnetic material pivoted loosely upon the said second magnetic member and adapted to be attracted to one end of the core which is suitably cut away to accommodate the said armature, means for preventing the said armature from sticking to the core after the magnetism has been removed, a second armature of thick magnetic material pivoted loosely upon the opposite side of the core from the said second magnetic member and adapted to be attracted to the said core, this last-mentioned armature overlapping the other armature when attracted and both armatures helping to complete the magnetic circuit when attracted, suitable adjustments and stops for the said armatures, to limit their movement, the said armatures being adapted to be operated upon different strengths of magnetism, respectively, in the said core, thus allowing them to be operated separately or together, and an inclosing shell adapted to fit over the said insulating heads and thereby inclose the electromagnet, substantially as described.
3. In an electromagnet, the combination of a magnetic core, a head of insulating material for each end of the core and placed thereon, an energizing winding carried by the core between the said heads, a second magnetic member secured to one end of the core by a bolt adapted also for mounting the electromagnet to a suitable support, and extending substantially parallel with the core, the said second magnetic member being secured to the said heads, an armature of thin magnetic material pivoted to the said second magnetic member so as to be attracted to the said core, a second armature of thicker magnetic material pivoted on the opposite side of the core from the said second magnetic member so as to be attracted to the said core, the said armatures overlapping each other when attracted and both helping to complete the magnetic circuit when attracted, suitable adjustments and stops for the said armatures, the said armatures being adapted to be attracted upon respective degrees of energization of the device whereby they may be operated separately or together, and an inclosing shell adapted to fit over the said heads to inclose the device as a whole.
4. In an electromagnet, the combination

- of a substantially U-shaped magnetic structure comprising a core and another magnetic member secured to one end of the core, a magnetizing coil wound upon the core, and two armatures at one end of the core both arranged to substantially complete the magnetic circuit of the U-shaped structure when attracted, one of the said armatures being pivoted to the said magnetic member, the other armature being pivoted on the opposite side of the core from the said magnetic member, the said armatures requiring respective degrees of energization of the electromagnet to effect their attraction. 12. In an electromagnet, the combination of a magnetic structure comprising a core and an L-shaped magnetic member secured to one end of the core, means for magnetizing the magnetic structure and two armatures arranged to substantially complete the magnetic circuit of the magnetic structure, one of the said armatures being operably attached to the said L-shaped member and the other armature being pivoted on the opposite side of the core from the L-shaped member, the said armatures requiring respective degrees of energization of the electromagnet to effect their attraction. 70
13. In an electromagnet, the combination of a magnetic structure comprising but a single core and an L-shaped magnetic member magnetically connected with one end of the core, means for magnetizing the magnetic structure, and two armatures arranged to substantially complete the magnetic circuit of the magnetic structure, one of the said armatures being operably associated with the said L-shaped member, the said armatures requiring respective degrees of energization of the electromagnet to effect their attraction. 75
14. In an electromagnet, the combination with an open magnetic structure, of two overlapping armatures therefor oppositely pivoted, adjacent the respective poles of the magnetic structure and adapted to substantially complete the magnetic circuit of the electromagnet when attracted. 80
15. In an electromagnet, the combination with an open magnetic structure comprising a single core having provisions for a return magnetic circuit along one side only of the core, of armatures therefor oppositely pivoted adjacent the respective ends of the said magnetic structure and overlapping each other to a certain extent. 85
16. In an electromagnet, the combination with a U-shaped magnetic structure, of armatures therefor oppositely pivoted adjacent the respective poles of the said magnetic structure. 90
17. In an electromagnet, the combination with an open magnetic structure comprising a single core having provisions for a return magnetic circuit along one side only of the core, of armatures therefor oppositely pivoted adjacent the respective poles of the said magnetic structure. 95
18. In an electromagnet, the combination with an open magnetic structure, of armatures therefor oppositely pivoted adjacent the respective poles of the magnetic structure and overlapping each other. 100
19. In an electromagnet, the combination with a substantially U-shaped magnetic structure, of armatures therefor pivoted adjacent the respective poles of the magnetic structure. 105
20. In an electromagnet, the combination 110
15. In an electromagnet, a magnetic core and energizing means therefor, an L-shaped magnetic member extending substantially parallel with the said core and secured to one end of the latter, and two armatures at the other end of the core pivoted on opposite sides thereof and arranged to substantially complete the magnetic circuit when attracted. 20
16. In a single-spool electromagnet having a core and an open magnetic circuit with provisions for extending the return magnetic circuit along one side only of the core, two armatures pivoted on opposite sides of the core and adapted to substantially complete the magnetic circuit when attracted. 25
17. In a single-core electromagnet having an open magnetic structure with provisions for extending the return magnetic circuit along one side only of the core, two separately-operable overlapping armatures oppositely pivoted adjacent the respective poles of the magnetic structure and adapted to substantially complete the magnetic circuit when attracted. 30
18. In a single-core electromagnet having an open magnetic circuit with provisions for extending the return magnetic circuit along one side only of the core, two armatures pivoted on opposite sides of the core and adapted to substantially complete the magnetic circuit when attracted. 35
19. In an electromagnet having but a single core with provisions for extending the return magnetic circuit along one side only of the core, two armatures at one end of the core pivoted on opposite sides thereof so as to be attracted thereto. 40
20. In an electromagnet having but a single core with provisions for extending the return magnetic circuit along one side only of the core, two armatures pivoted on opposite sides of the core and adapted to be attracted thereto. 45
21. In a single-core electromagnet having an open magnetic circuit with provisions for extending the return magnetic circuit along one side only of the core, two armatures oppositely pivoted and adapted to substantially complete the magnetic circuit when attracted. 50

with an open magnetic structure, of armatures therefor pivoted adjacent the respective poles of the magnetic structure and overlapping each other.

5 21. In an electromagnet having a core and means for energizing the same, two overlapping armatures adapted and arranged to be attracted by the end surface of one end of the core, the said end of the core having 10 a portion thereof cut away on one side thereof for accommodating one of the armatures

whereby different portions of the end surface of the said end of the core are in close proximity to the respective armatures for attracting them.

15

In witness whereof I hereunto subscribe my name this 16th day of February, A. D. 1904.

FREDERICK R. PARKER.
